DIESEL HAMMER

William V. Spurlin, Indiana, Pa., assignor to Syntron Company, Homer City, Pa., a corporation of Delaware

Application July 22, 1949, Serial No. 106,207

9 Claims. (Cl. 123—7)

1

The diesel hammer comprising this invention has a cylinder with a freely moving piston therein which functions as a ram striking an anvil that closes the lower end of the cylinder and defining a diesel power cylinder between the end of the piston and the anvil. The upper end of the cylinder is closed and the upward stroke of the piston is employed for compression, part of its stroke functioning to produce scavenging air for the power cylinder and another substantial part of the piston stroke compresses a considerable volume of air in a reservoir or clearance volume, which energy is later returned to the piston.

The reservoir or clearance volume is associated with and external to the cylinder proper and connected thereto by means of ports. This construction shortens the overall length of the hammer.

The closing of the ports by the piston provides an air lock between the end of the piston and the cylinder closure which in turn provides a stroke limiting means.

The value of the compression ratio in the reservoir is determined from an energy balance at full load. On the power stroke the output of the power cylinder is stored in the form of the potential energy, that is, the piston weight times the stroke, plus the energy stored in the form of compressed air in the reservoir, minus friction and scavenging losses. On the work stroke this energy minus friction minus scavenging intake losses and minus the work of compression in the power cylinder equals the useful work expended by impact of the piston on the anvil.

The relatively large volume of low pressure air compressed in the reservoir makes possible the most efficient use of the weight of the housing and external parts attached thereto as a constant resisting force permitting the hammer to operate at full load without excessive bouncing on the object being impacted. This method produces an effect similar to a constant force spring working over a long travel.

It has been found from actual operation and calculation that the compression ratio in the compression end of the hammer may be 1.75:1 to 2.5:1 for 4' to 2' strokes on hammers designed to operate at full load without an additional external load or force required to keep the hammer in contact with the work.

For hammers designed to work at full load with an external load or force to keep the hammer in contact with the work the stroke should be reduced by using compression ratios of 2.5:1 to 5:1.

Although the hammer does not operate on a

true double acting principle, that is energy added at both ends of the piston, the energy output and frequency of movement of the piston is comparable to a double acting hammer since a very substantial amount, ranging from 40% to 95%, of the available energy is stored in the form of compressed air and recovered on the return stroke.

This arrangement, having a combustion chamber supplied from a single injection pump at but one end and an energy storing means at the other end produces impact forces both as to value and frequency comparable to a hammer of the double acting type having a combustion chamber at both ends and requiring two injection pumps and also comparable in size and weight thereto. Another advantage as compared to the double acting hammer of the same output would be a lower surface area to displacement volume ratio of the combustion chamber giving less heat loss thereby providing easier starting and higher thermal efficiency.

Fuel is injected into the combustion chamber just before the piston strikes the anvil. The timing of the injection of fuel and the opening and closing of the ports by the piston provides a novel operating cycle of this diesel hammer.

When the piston is ascending, scavenging air is transmitted through two passages and blows downwardly through a series of directional semi-circularly arranged ports that cause the air to loop down into and back up the power cylinder before being expelled through the exhaust port immediately following the exhaust of the products of combustion leaving fresh air for the next combustion cycle. Further upward movement by the piston produces a small influx of air into the power cylinder through the exhaust port which is afterwards expelled by the descending stroke of the piston.

Under certain conditions where the total stroke is long compared to the power stroke, and remains almost constant from idle, to full load, it may be desirable to eliminate the scavenging portion of the cylinder and use that part of the stroke in the power cylinder from the opening of the exhaust ports to the total stroke for the purpose of scavenging.

When the products of combustion and the scavenging air are expelled from the exhaust port they are directed through a nozzle on a housing that encases the cylinder which has longitudinally disposed radial fins. This nozzle confines the fluid pressure discharge to the atmosphere which in turn functions as an intermittently operating ejector, drawing air past the fins

and around the cylinder, thereby functioning to cool the cylinder.

This piston functions on its downward stroke to actuate the fuel and lubricating pumps by operating one lever. The fuel pump in turn operates two fuel injectors and the lubricating pump distributes lubricating oil to several parts of the cylinder.

The fuel injectors discharge a metered quantity of fuel into upwardly open semispherically shaped chambers in the top of the anvil which is in effect a piston slideable in the cylinder within limits determined by a retaining ring that also prevents the anvil piston from rotating. The upwardly open semispherically shaped chambers are adjacent a projection on the anvil which extends into a complementary space hollowed out of the bottom of the piston. When the latter descends this space is filled by the projection on the anvil and the displaced air rushes downwardly in fixed tangential paths into the upwardly open semispherical chambers at the same time that the fuel is injected therein. This turbulent action of air into which the fuel is injected creates mixing of the fuel with air and the high temperature generated by compression causes the mixture to ignite as the piston strikes the anvil.

The piston is initially raised by a dead center linkage device that automatically trips when the piston is part way up its stroke. The particular arrangement of elements making up this diesel hammer permit it to operate on a minimum idling stroke which is barely enough to fully open the exhaust port. By controlling the quantity of fuel per injection, the hammer can be readily controlled as to stroke and percussive power.

While, for the sake of clearness in illustration, the hammer is shown and described in use as a pile hammer with the cylinder in a substantially upright position, but it is obvious that the hammer may be arranged to operate in a position inclined to the vertical as may be required for various types of uses to which the hammer is applicable.

Other objects and structural advantages are disclosed in the accompanying drawing, description and claims.

The accompanying drawings show, for the purpose of exemplification without limiting the invention or claims thereto, certain practical embodiments of the invention wherein:

Figs. 1 and 1a provide a continuous view in vertical section of the diesel hammer comprising this invention;

Fig. 2 is a view in vertical section of another portion of the hammer with parts broken away;

Fig. 3 is an enlarged view of the piston lifting linkage shown in Fig. 2;

Fig. 4 is a cross-sectional view taken on the line 4-4 of Fig. 1a;

Fig. 5 is a cross-sectional view taken on the line 5-5 of Fig. 1a;

Fig. 6 is a cross-sectional view taken on the line 6-6 of Fig. 1a;

Fig. 7 is an enlarged view in front elevation taken from the plane 7-7 of Fig. 1a showing the exhaust port;

Fig. 8 is a cross-sectional view taken on the line 8-8 of Fig. 1;

Fig. 9 is an enlarged view partly in section of the fuel and lubricating pumps;

Fig. 10 is a sectional view of the fuel pump hydraulic remote control;

Fig. 11 is an enlarged sectional view illustrating the fuel tank; and

Fig. 12 is a diagrammatic view illustrating a pressure indicating card of the operating cycle of the diesel hammer.

Referring to Figs. 1 and 1a, the diesel hammer consists of the piston or ram 1 which is free to reciprocate in the cylinder 2. This piston is preferably of the differential type as shown but may be constructed as having a single diameter. The small diameter section 3 at the power end of the cylinder is equipped with rings 4 and operates in the power cylinder 5. The upper or large end of the piston 6 is equipped with the rings 7 and operates in the compressor chamber 8. The two sections of the differential piston form the intermediate annular shoulder 9.

The cylinder 2 is preferably made up of two parts corresponding to the two sections of the differential piston. The lower cylinder section 10 contains the power cylinder 5 and the upper and larger cylinder section 11 contains the compressor chamber 8.

The lower end of the cylinder section 10 is closed to complete the power cylinder by the anvil 12 which is actually a second piston provided with rings 13 and slideable between limits in the lower end of this cylinder.

As shown in Figs. 1a and 4, the anvil 12 has the oppositely disposed slots 14 and 15 adjacent its annular striking head 16 which engages directly on the piling 17. These slots have the keys 18 and 19 extending thereinto, said keys being integral or attached to the ring halves 20 and 21 which are bolted with the piling guide ring 22 to the lower annular flange 23 of the cylinder. The bore of the guide ring 22 is tapered as indicated at 24 to center and retain the top of the piling under the head 16 of the anvil. The bore of the flange 23 of the cylinder 10 is tapered as indicated at 25 to permit the cylinder 2 to be lowered down over the anvil 12, the tapered bore 25 compressing the rings 13 for entering the cylindrical bore. When the anvil 12 has been inserted the half rings 20 and 21 are positioned and are bolted to the cylinder with the guide ring 22.

The top of the anvil has two upwardly open turbulent chambers 26 and 27 on opposite ends of a projection 28 that extends above the piston striking surface 30 of the anvil. As shown in Figs. 1a and 5, these turbulent chambers are each cylindrical at the top and the bottom is semispherical. The cylindrical outline of the top follows up each side of the projection 28 forming the grooves 31 and 32 as shown in Fig. 5. The bottom surface of the piston 1 has the recess 33 to receive the projection 28 of the anvil. Clearance is made between the walls of the recess 33 and the projection 28 but the grooves 31 and 32 form the general avenue of escape for the air when displaced as the piston descends. The air displaced is forced down the grooves and swirls in circular paths within the turbulent chambers 26 and 27. At this time the injectors 34 and 35 receive a metered quantity of fuel from the matched sections of the line 36 leading from the fuel pump 37. The metered quantity of fuel is atomized by injection and is thoroughly mixed with the turbulent air. The compression being sufficiently high and the injection properly timed by the arrangement of parts create combustion of the fuel at about the time the piston strikes the surface 30 of the anvil.

The combustion of the fuel forces the piston

1 upwardly and when its bottom edge reaches the lower end of the exhaust port 38 which is shown in the form of four independent openings each hooded as indicated at 40, the useful energy having been transferred from the burning gases to the piston by this time causes the piston to complete its expansion stroke. The length of the stroke of the piston, together with the work it must perform, is of course determined by the amount of fuel supplied per cycle. A large quantity of fuel will send the piston to the extreme limit of its stroke in a hurry and perform all the work required of it; whereas a relatively small amount of fuel will cause the piston to approach the top of the exhaust port 38 and thus continue to operate without impact on the anvil which is considered to be an idling condition.

As shown in Figs. 1a and 6, the power cylinder 5 is provided with a semicircular series of downwardly directed scavenging ports 41. The top and bottom margins of these ports slope downwardly as they pass through the lower cylinder 10 and the arcuate manifold 42 traversing the scavenging ports on the outside of the cylinder also has downwardly sloping walls. Thus, the piston starts to uncover the exhaust port 38 and the products of combustion, which still represents a gaseous pressure, flow out the exhaust port. Further upward movement of the piston uncovers the scavenging air ports 41 and the air rushes down on one side of the power cylinder forcing the balance or residue of the products of combustion up the other side of the power cylinder and out the exhaust port. At about the time the bottom of the piston reaches the top of the scavenging air ports 41, the top of the piston has closed off the scavenging air ports 43 in the compressor chamber 8. The ports 43 are likewise disposed in an arcuate fashion and are connected on the outside by the arcuate manifold 44. The ends of the arcuate manifolds 42 and 44 are connected by the tubes 45 and 46 as indicated in Figs. 1 and 8. The dual or split conduits or passages 45 and 46, together with the arcuate manifolds at the ends, provide a uniform distribution of the scavenging air into the power cylinder 5. Thus, the scavenging air stroke of the piston 6 extends from the position shown in Fig. 1 until the ports 43 are closed.

As said stroke of the piston continues it displaces the air through the arcuate series of ports 47 to the opposed air tanks 48. This displaced volume of air becomes compressed with the air in the tank 48 thereby storing energy and also providing an initial cushioning action of the piston. If the piston is energized to move beyond the ports 47 thus closing them off it compresses the air trapped at 49 between the head 50 and the top of the piston thus quickly compressing the air to a high pressure causing a quick stop of the piston before it strikes the head 50. The small amount of air trapped for cushion and stop purposes and the large volume of air previously compressed in the tank 48 prevent the generation of considerable heat, thereby reducing the losses of the hammer which is an important object of this invention. As the piston descends it uncovers the ports 47 whereupon the air compressed in the twin tanks 48 delivers its energy to the piston. Further return movement of the piston starts to uncover the compressor scavenging ports 43. At this position the compressor chamber 8 is drawing a slight vacuum and a small influx of air may travel back up the passages 45 and 46 from the combustion chamber before the

ports 41 are closed. The piston continues to fall until it strikes the surface 30 on the anvil to drive the pile. The length of the grooves 14 and 15 provides sufficient travel of the anvil to prevent transferring the initial impact to the cylinder and external parts without causing the upper ends of the groove to engage the half rings 20 and 21. In fact, the cylinder 2 follows the anvil so closely that it is not jarred or bumped which is one of the important advantages in the operation of the hammer.

It will be noted in Fig. 1 that the upper ends of the cylinder sections 10 and 11 are beveled at 51 and 52. The beveled surface 51 is for the purpose of compressing the rings 4 to fit in the power cylinder 5 and the beveled surface 52 is to compress the rings 7 of the larger end 6 of the piston as it is lowered in the top of the cylinder 1 in assembling the hammer. These cylinder sections as well as the head 50 are bolted together and the cylinders have interfitting parts as indicated at 53 which align said sections.

In starting the piston is raised by a hoist to an elevation required to obtain enough energy for the first compression stroke in the power cylinder 5. This is accomplished by the carriage 54 slideable in the tubular channel 55 preferably totally enclosed on the side of the cylinder 11 as shown in Fig. 2. The channel 55 does not interfere with the arcuate manifold 44 but it extends for a substantial distance along the cylinder 11 and lies between the conduits 45 and 46. An extension tubing 56 passes from the channel 55 through the tank 48. The carriage 54 is lifted by the cable 57 which has an eye on its upper end for the purpose of receiving a hoist hook. The channel 55 is circular in cross section and a longitudinal portion 58 thereof is opened into the bore of the cylinder 11. The bottom of the channel 55 is closed by the casing extension 60 which is attached to the cylinder section 10 and fits the bottom of the channel 55 attached to the cylinder section 11 as shown in Fig. 3.

The carriage 54 is cylindrical in horizontal cross-section and is provided with an irregular longitudinal groove 61 formed to receive the several links and levers making up the lift. The cable 57 is held by the cross pin 62 and the lever 63, which is a single member pivoted on the pin 64 and having recesses on each side thereof to receive a pair of links 65 pivoted at their upper ends on the pin 66 passing through the intermediate portion of the lever 63. The lever 63 extends through the slot 58, and is never out of engagement therewith which prevents rotation of the carriage 54, and engages under the shoulder 9 of the piston 1. The tip of the lever 63 is depressed to provide a heavy cross-section at the pin 66. The lower ends of the pair of links 65 are pivotally connected to the pin 67 that is mounted in the upwardly extending arm 68 of the bell crank lever 70 which in turn is journaled on the pin 71 extending through the carriage 54. Thus, three pins 62, 64 and 71 are mounted in the carriage. The other arm 72 of the bell crank is bifurcated and extends outwardly into the slot 58. The overall width of the bifurcated arm 72 of the bell crank lever 70 is greater than that of the lifting lever 63. Thus, the prongs of the lever 72 engage the shoulders 73 on each side of the slot 58 as shown in Fig. 2 when the carriage 54 is elevated to its upper limit of travel; whereas the left arm 63 passes between said shoulders.

The pivotal centers of the pins 66, 67 and 71 lie in an over dead center alignment when the lower end of the pair of links 65 and bell crank arm 68 engage the abutment lug 74 in the slot 61 of the carriage. When the links are in this position the arm 63 will be extended and engage under the shoulder 9. A detent is provided on the hub of the bell crank lever 70 to hold the arm 63 extended until weight is assumed by the arm 63. The piston 6 may revolve in its cylinder so the arm 63 may not always engage the piston at the same spot. When the piston is raised until the top thereof is above the scavenging ports 53, the prongs of the bifurcated lever 72 engage the stop shoulders 73 causing the bell crank to swing clockwise past dead center alignment, thus dropping the arm 63 and allowing the piston to fall. A hoist is used to hook on the cable 57 for the purpose of lifting the piston.

When the carriage is lowered it strikes the rubber bumper 75 in the bottom of the casing 60. The bifurcated arm 72 of the bell crank lever 70 will be extending downwardly but it will not swing counterclockwise until the hand line 76 is pulled to rock the lever 77 and raise the spring biased pin 78 into position to engage the arm 72 and rock the bell crank 70 counterclockwise to extend the arm 63 in horizontal locked position. The shoulder 9 of the piston stands above the intersection of the two cylinders 10 and 11 which provides ample room for the arm 63 to swing up into place as shown in Fig. 3. Thus, one must hand set the lifting mechanism before the piston can be raised. Manual latching is used in order to prevent accidental engagement of lever 63 with shoulder 9 while the hammer is operating.

When the piston 1 falls in cylinder 2, the upper section 6 adjacent the shoulder 9 engages the bell crank lever 80 along the cam surface 81 of the upper arm 82. This lever 80 is pivoted on the pin 83 in the slot 84 at the bottom of the cylinder section 11. The lower arm 85 of the bell crank engages the plunger 86 of the fuel injection pump 37 to supply a metered quantity of fuel to the injectors 34 and 35. The arm 85 has a detachable hand lever 87 for operating the fuel pump 37 to manually prime the system. The fuel is fed to the pump 37 by gravity through the line 88a from the tank 88 attached to the cylinder 11 below the twin air chamber tanks 48. The fuel passes through the filter 89 removably mounted in the bottom of the tank as shown in Fig. 11.

The upper lever arm 82 of the bell crank 80 has the link 90 pivotally connected thereto. The other end of the link is in turn pivotally connected to the arm 91 that actuates the ratchet 92 of the lubricating pump 93. Several distribution lines 94 conduct the lubricating oil to several points on the cylinder to lubricate the piston's movement. The lubricating oil is likewise fed by gravity from the tank 95 through the strainer 96 and the line 97. Thus, the piston feeds itself fuel at the same time that it supplies lubricant to the cylinder for its own operation which provides a novel structure of this disclosure.

The sides of the cylinder 2 opposite to that of the injectors, fuel pump and scavenging air passages are provided with the longitudinal guides 98 as shown in Fig. 5 for mounting the hammer in a frame having ways to receive the guides. This frame may be supported on skids to facilitate handling the hammer and frame. The top of the hammer is provided with the

hoisting connection 99 as shown in Fig. 1 for raising or otherwise handling the mechanism with a hoist line.

As shown in Fig. 12, the complete operating cycle of the combustion and compressor ends of the hammer fuel injection is indicated at 100 where the compression has substantially reached its maximum at 101. The upward expansion stroke follows along the dotted line to 102 where the exhaust port 38 begins to open discharging the products of combustion. At the same time the compressor starts to compress air from 100 to 103 where the scavenging ports 41 open to aid in blowing out the power cylinder until the scavenging ports 43 are closed at 105. The power cylinder reaches atmospheric pressure at 104 after ports 43 are closed and remains in this pressure state until pressure starts to build up in the power cylinder when the piston is on its downward stroke and before the exhaust port 38 is closed as indicated. In the upper end of the piston stroke the power cylinder stays at a constant pressure so the line travels to 106 and back to 105. In the compressor phase the pressure increases from 105' to 107 after which the ports 47 are closed and the small volume of air at the top of the cylinder quickly rises to a high pressure 108 and then the piston reverses following back almost along the same line except for unrecoverable losses to 105' and when the top of the piston is passing the scavenging ports 43 the chamber 8 is drawing a slight vacuum; thus the pressure falls rapidly below the atmospheric line to 109 where the filtered compressor inlet 49 opens and the air rushes in to fill the chamber 8 by the time the piston strikes the anvil as indicated at 100. In the power cylinder the pressure starts to rise before the exhaust ports are closed and continues to rise to point 101 where the piston engages the anvil, injection of fuel is made and combustion takes place.

The outer surface of the cylinder section 10 has a series of longitudinally disposed fins 110 as illustrated in Figs. 1a and 5. These fins extend from above the exhaust port to above the flange 23 which amounts to the major exterior portion of the power cylinder 5. At the level of the center of the exhaust port 38, the fins are notched out to form a circular groove 111 which widens at the ports 38. A cover 112 completely surrounds the fins 110 and encloses the same for their full extent. The upper end of the cover is attached to lugs 113 spaced around the cylinder but the cover is open at the lower end as indicated at 115 to receive air. The lower ends of the spaces between the fins are closed by the cylinder preheating ring 114 but the lower edge of the cover 112 is spaced from the ring leaving an annular port 115. When the piston strikes the anvil and ignites the fuel by compression causing the piston to travel up the cylinder the products of combustion pass out through the sleeves 40 surrounding the exhaust ports 38 and pass out the ejector nozzle 116 which is formed integral with the cover 112 and surrounds the exhaust ports, the rapid movement of gases creating a suction drawing air from both ends of the casing past the fins 110 to cool the power cylinder 5. The ejector nozzle 116 has a flared mouth 117 and extends sufficiently beyond the cover 112 to produce a good suction without impeding the exhaust. The nozzle also extends far enough to protect the cylinder and piston from weather although the sleeves and the nozzle should be capped if the device stands idle.

The amount of fuel injected per stroke is controlled from the ground level, in the case of a diesel hammer, by a hydraulic remote control system. This system consists of a manually actuated transmitter hydraulic cylinder 118 mounted at ground level and connected by a hydraulic flexible hose 119 to a receiver hydraulic cylinder 120 which has an actuating arm 121 connected by suitable linkage 122 to the fuel pump rack 123. The rack rotates the fuel pump plunger 124 causing the plunger helix 125 to uncover the bypass port 126 thereby in effect varying the displacement of the pump from zero to maximum discharge.

The hydraulic remote control provides accurate control of the output of the hammer and is easily operated for long distances between control station and the hammer. It also provides an automatic shutdown in case of accidental breaking of the hydraulic hose thereby preventing damage that would be caused by an uncontrolled hammer.

The output of the hammer varies with the stroke which in turn is controlled by the amount of fuel injected per stroke. At idle or without impact the piston rises only to the top of the exhaust ports in the power cylinder increasing to the full stroke with a corresponding increase in the quantity of fuel injected.

For extreme cold weather starting the cylinder preheating ring 114 is provided at the lower end of the power cylinder. The preheating ring may be filled with fuel and ignited to produce an annular fire to heat the cylinder wall to the temperature required for easy starting.

While, for clarity of explanation, certain preferred embodiments of this invention have been shown and described, it is to be understood that this invention is capable of many modifications, and changes in the construction and arrangement may be made therein and certain parts may be employed without conjoint use of other parts and without departing from the spirit and scope of this invention.

I claim:

1. A diesel power hammer comprising a tubular member closed at its one end, a pile engaging anvil closing the other end of said tubular member, a percussion piston free to reciprocate in said tubular member and strike said anvil, fuel injection means to supply fuel between the anvil and the percussion piston where it is ignited, and a closed fluid energy storing and redelivering tank connected to the closed end of said tubular member to receive and store energy in a large volume of fluid under pressure when the percussion piston moves away from the anvil and redeliver the stored energy to the piston on its return stroke.

2. A diesel power hammer comprising a tubular member closed at its one end by a pile engaging anvil and closed at its other end to form an air compression chamber, a percussion piston free to reciprocate in said tubular member and strike said anvil, fuel injection means to supply fuel between the anvil and percussion piston where it is ignited, and a closed energy storing and redelivering compression tank having a connection with said air compression chamber and located in a position to be shut off by the movement of the piston before reaching the end of its stroke toward the second mentioned end of the cylinder.

3. A diesel power hammer comprising a tubular member closed at its one end by a pile engag-

ing anvil and closed at its other end to form an air compression chamber, a percussion piston free to reciprocate in said tubular member and strike said anvil, fuel injection means to supply fuel between the anvil and the percussion piston where it is ignited to move said percussion piston toward the second mentioned end of the cylinder, and a laterally disposed energy storing and redelivering chamber having a connection only 10 with the air compression chamber of said tubular member that is positioned to receive only a portion of the gases compressed by the percussion piston.

4. A diesel power hammer comprising a tubular member closed at its one end by a pile engaging anvil to form a combustion chamber and closed at its other end to form an air compression chamber, uninhibited inlet and outlet ports in the air compression chamber of said tubular member, scavenging air inlet and direct exhaust ports in the combustion chamber end of said tubular member, all of said ports in the wall of said tubular member, a percussion piston free to reciprocate in said tubular member to open and close each of said ports by sliding past the same and to strike said anvil, and conduit means connecting the scavenging air outlet and inlet ports in the air compression chamber and combustion chamber ends, respectively, of said tubular member.

5. A diesel power hammer comprising a tubular member closed at its one end to form an air compression chamber with inlet and outlet ports and closed at its other end by an anvil to form a combustion chamber with inlet and exhaust ports, a percussion piston free to reciprocate in said tubular member to open and close said ports and strike said anvil, the inlet and exhaust ports being positioned diametrically opposite in the walls of the combustion chamber, and said combustion chamber inlet port receiving compressed gases from said air compression chamber outlet ports and shaped to direct the gases toward the anvil and in the direction of the exhaust to form a loop of scavenging air through the combustion chamber when the ports of the latter are open.

6. A diesel power hammer comprising a cylinder closed at the top, an anvil member closing the bottom of the cylinder and having limited movement therein, a percussion piston member free to reciprocate in the cylinder and defining a combustion chamber at the bottom and an air compression chamber at the top of said cylinder, an inlet port for said air compression chamber, a scavenging passage having a port in each chamber at each end to connect both of said chambers, a closed fluid tank connected through a port to the air compression chamber, an exhaust port in the cylinder wall above the anvil member, the reciprocating percussion piston member opening and closing all of said ports, the scavenging passage port in the air compression chamber being constructed to be closed by the percussion piston member before the port to said closed fluid tank is closed, fuel injection means actuated by the piston to supply fuel to the combustion chamber which is ignited about the time the percussion piston member strikes the anvil member, the exhaust port being constructed to be initially opened by the percussion piston member on its upward stroke before opening the scavenging port.

7. A diesel power hammer comprising a cylinder closed at the top, an anvil member closing the bottom of the cylinder and having limited move-

ment therein, a percussion piston member free to reciprocate in the cylinder and defining a combustion chamber at the bottom and air compression chamber at the top of said cylinder, an inlet port for said air compression chamber, a scavenging passage having a port in each chamber at each end to connect both of said chambers, an exhaust port direct to atmosphere in the combustion chamber wall above the anvil member, the reciprocating percussion piston member opening and closing all of said ports by sliding past the same, fuel injection means actuated by the piston to supply fuel to the combustion chamber which is ignited about the time the percussion piston member strikes the anvil member, the exhaust port being constructed to be initially opened by the percussion piston member on its upward stroke before opening the scavenging port.

8. A diesel power hammer comprising a cylinder with uniform bores at the ends thereof, a flat transverse member closing the bore at the top, an anvil member closing the bore at the bottom and having limited axial movement therein, a percussion piston member free to reciprocate in the cylinder to engage both end members, said percussion piston member defining a combustion chamber with the bottom and an air compression chamber at the top of the cylinder, an inlet for said air compression chamber, a scavenging passage having a port in each chamber at each end to connect both of said chambers, an exhaust port for said combustion chamber, a closed fluid tank connected through a port spaced from said flat transverse member to produce an air cushion at the end of the cylinder to prevent the percussion piston member from engaging the flat transverse member, said percussion piston member opening and closing all of said ports, said percussion piston member creating a rebound cushion with said flat transverse member after compressing a large volume of low pressure air in said closed fluid tank and closing the port thereof.

9. A diesel power hammer comprising a cylinder closed at the top, an anvil member closing

the bottom of the cylinder and having limited movement therein, a percussion piston member free to reciprocate in the cylinder and defining a combustion chamber at the bottom and an air compression chamber at the top of said cylinder, an inlet for said air compression chamber, a scavenging passage having a port in each chamber at each end to connect both of said chambers, an exhaust port in the combustion chamber, the reciprocating percussion piston member opening and closing all of said ports by sliding past the same, fuel injection means actuated by the piston to supply fuel to the combustion chamber which is ignited about the time the piston strikes the anvil member, the operation of the scavenging passageway port and said exhaust port in the combustion chamber being substantially coextensive by being opened and closed in unison, and the passage port in the air compression chamber being positioned to be closed when the combustion chamber ports are fully open to permit the hammer to idle with a stroke that partially opens the exhaust port.

WILLIAM V. SPURLIN.
